EX
OR D 859

Design

Patented Dec. 23, 1856.

N° 859.

In present of Dennis W. Mills
Richard Green

Antoine Blouin

UNITED STATES PATENT OFFICE.

ANTOINE GLOMINSKI, OF LANSINGBURG, NEW YORK, ASSIGNOR TO
D. POWERS, A. E. POWERS, AND N. B. POWERS.

DESIGN FOR FLOOR-CLOTH.

Specification forming part of Design No. 859, dated December 23, 1856.

To all whom it may concern:

Be it known that I, ANTOINE GLOMINSKI, of Lansingburg, in the county of Rensselaer and State of New York, have invented and produced a new Design, Pattern, or Figure to be Printed, Stamped, or Used upon Floor Oil-Cloths or other Fabrics; and I do hereby declare the following to be a full and exact description of the same, reference being had to the annexed drawing, viz:

The pattern or figure is made up of two principal objects—an octagon and a square laid diamondwise—which are separated from each other by a raised band or molding, upon which is placed another ornamented belt of colors so arranged as to represent a rounded molding carved in arabesque figures. The

leading figure is the octagon, which is of plain ground with a group of flowers and leaves in natural colors upon it. The square is also of plain ground and has a rosette placed upon it of colors differing from the ground. The whole detail and effect of the pattern are only shown when repeated.

What is claimed as my invention, and desired to be secured by Letters Patent of the United States, is—

The arrangement of ornamental figures forming a design for floor oil-cloths or other fabrics, as shown in the aforesaid drawing.

ANTOINE GLOMINSKI.

Witnesses:

JAMES W. MILLS,
RICHARD GREEN.
